DASHPOT CONTROL FOR VEHICLE ENGINE
THROTTLE VALVESThomas M. Ball, Detroit, Mich., assignor to
Chrysler Corporation, Highland Park, Mich., a
corporation of Delaware

Application March 14, 1951, Serial No. 215,595

11 Claims. (Cl. 180—77)

1

This invention relates to throttle valve control devices to be used especially in conjunction with motor vehicle internal combustion engines and deals particularly with a control for throttle valve closing movement.

It is well known at this time that an internal combustion engine has a tendency to stall when, at relatively low vehicle speeds, the driver suddenly releases the usual accelerator pedal to allow the throttle valve to suddenly close. This engine stalling tendency is known to be especially pronounced in motor vehicles equipped with a fluid coupling through which the drive is transmitted.

Heretofore, it has been customary to provide some form of dashpot for retarding the last part of throttle valve closing movement so that when the accelerator pedal is suddenly released, the throttle valve has its final closing movement retarded so that the fuel supply system and other factors which are disturbed and which give rise to engine stalling have an opportunity to become balanced or adjusted to the coast drive conditions whereupon the throttle valve may thereafter close without danger of engine stall.

The foregoing throttle retarding devices have the disadvantage that they also operate at relatively high vehicle speeds thereby preventing full use of the engine as a coast brake due to the fact that when the accelerator pedal is released, the throttle valve does not fully close until after an appreciable time during which the aforementioned dashpot acts. Furthermore, where the vehicle is equipped with a change speed mechanism that functions as a result of allowing the engine to coast down in its speed, the foregoing dashpot device has the disadvantage of increasing the time required to effect changes in the speed ratio drive due to the dashpot delaying the engine speed retardation.

In my copending patent application Serial No. 643,819 filed January 26, 1946, now U. S. Patent 2,592,375, and in my previously issued U. S. Patents Nos. 2,314,570 and 2,334,857, I have provided dashpot controls for engine throttle valve closing movement that overcome the aforementioned difficulties. In each of the above-noted patents the dashpot controls incorporate means for rendering the dashpot ineffective for throttle closing retardation at times such as high vehicle speeds when the engine does not tend to stall as an incident to sudden release of the accelerator pedal. The above-noted dashpot controls have the dashpot mechanisms associated with either the liquid fuel in the carburetor body or with the manifold vacuum of the fuel intake manifold and

2

as a consequence certain troublesome problems associated with these engine charging media enter into the operation of the dashpot controls. Furthermore, due to the type of operating media used in the dashpots of the above noted dashpot constructions, it is practically imperative that the dashpot devices be formed integrally with or be directly mounted on the associated carburetor device. It is thought to be obvious that it may be more convenient and more economical to mount the throttle valve control dashpot at a location remote from the carburetor provided the same degree of throttle control can be secured.

It is a primary object of this invention to provide an improved and simplified form of dashpot control for throttle valve closing movement that is disassociated from the fuel media, liquid or gaseous, that passes from the carburetor into the vehicle engine.

It is a further object of this invention to provide an air dashpot to control throttle valve closing movement which dashpot may be located at any point on the vehicle where it may engage an element of the throttle valve control linkage.

It is another object of this invention to provide an air dashpot for control of the engine throttle valve closing movement which dashpot has a vehicle speed responsive by-pass valve associated with the dashpot in such a manner that retardation of throttle valve closing movement is practically inconsequential at certain vehicle speeds while being a major influence at other predetermined vehicle speeds.

It is still another object of this invention to provide an improved, simplified form of dashpot having valve means associated therewith to provide means for varying the cushioning effect of the dashpot.

It is still another object of this invention to provide a simplified, improved form of dashpot having novel valve controlled means to transfer the dashpot operating medium between opposed, diaphragm separated, chambers of the dashpot.

It is still another object of this invention to provide a novel form of throttle valve control device that is particularly adapted for use with automatic or semi-automatic types of transmissions wherein the changes in speed ratio drive are controlled by or effected through release of the accelerator pedal.

Other objects and advantages of this invention will become readily apparent from a reading of the attached description and a consideration of the related drawings wherein:

Fig. 1 is a diagrammatic side elevational view

of a motor vehicle internal combustion engine and its associated power transmission elements that include a throttle valve dashpot device in accordance with this invention;

Fig. 2 is an enlarged sectional elevational view of the dashpot device embodying this invention;

Fig. 3 is a side elevation of the dashpot device, the view being taken in the direction indicated by the arrow 3 of Fig. 2;

Fig. 4 is a schematic wiring diagram for the electrically operated controls for the dashpot device shown in Figs. 1-3;

Fig. 5 is a sectional elevational view of a semi-automatic type of power transmission unit that is particularly adapted for use with a throttle valve controlled by an air dashpot of the type herein disclosed; and

Fig. 6 is a diagrammatic view, partly in sectional elevation, of the control system for the power transmission unit shown in Fig. 5.

My invention may be used advantageously in connection with any vehicle power transmission system. In my aforesaid copending application and in my patents I have illustrated one type of drive system that is well adapted for use with my present improvements. However, in order to illustrate the principles of my present invention I have merely shown the same in connection with a schematic vehicle drive mechanism in Figs. 1-4, it being understood that this drive mechanism may take a variety of forms although it is especially adapted for drive systems of the type shown in Figs. 5 and 6 where, at times, it is desired to allow the engine to rapidly slow down upon release of the accelerator pedal without any retarding of throttle closing movement by the dashpot control while at other times it is desired to retard throttle closing movement to prevent tendency of the engine to stall.

In Fig. 1 the customary internal combustion engine A is arranged, as is now well known, to drive through suitable clutch mechanism B and/or any desired type of transmission change speed mechanism C to the output or propeller shaft 20 which is adapted to drive the usual vehicle driving wheels in accordance with standard practice. The clutch mechanism at B may comprise a slip-drive device such as a fluid coupling, a torque converter, a conventional friction clutch or any combination of these elements.

The engine intake manifold 21 is fitted with an air cleaner 22 and carburetor D having the usual throttle valve 23 mounted in the throat 30 thereof on the rotatable shaft 29. Shaft 29 supports and is adapted to be operated by the lever 24 and the link 25 that are connected by linkage 26 to the conventional accelerator pedal 27. Accelerator pedal 27 is yieldingly urged by compression spring 28 to a position that tends to close the throttle valve 23.

Mounted on the side of the carburetor D, (see Figs. 2 and 3), by means of the screw attached bracket plate 35, is my novel form of dashpot device E that is adapted to control the closing movement of the throttle valve 23. The dashpot device E comprises a two-piece casing formed of the mating, dished casing parts 36 and 37. Casing parts 36 and 37 are adapted to be suitably secured together by screws or the like with a flexible diaphragm member 39 mounted therebetween. The diaphragm 39 divides the chamber within the casing into two compartments 41 and 42 respectively.

Casing part 36 has an externally threaded neck portion 43 that extends through a suitable open-

ing 35a in the support plate 35. The casing neck portion 43 is pierced by an axially extending bore 44 that loosely receives the plunger rod 45. Plunger rod 45 has its interiorly disposed end 46 connected to the diaphragm 39 in such a manner that movement of the diaphragm 39 is transmitted to the plunger rod 45. The interiorly disposed end portion 46 of plunger rod 45 is pierced by an axially extending bore 47 that is adapted to provide a conduit connection between the chambers 41 and 42 of the dashpot device E. Bore 47 in plunger rod 45 is connected to a radially extending cross-bore 48 that connects the plunger rod bore 47 to the bore 44 in the casing neck portion 43. Loosely mounted in the plunger rod cross bore 48 is a pin or plug element 49. Pin 49 converts the cross bore 48 into a restrictive opening that meters or controls the transfer of air from the chamber 41 to the chamber 42 through the bore or passageway 47. It is obvious that one or more very small cross-bores (not shown) could be connected to the rod bore 47 instead of the large pin blocked across bore 48. The pin blocked construction has the advantage that it is easy to drill without danger of breaking the drill bits and furthermore different sized pins or plugs may be mounted in the large cross bore 48 to vary the metering action on the air or the fluid medium passing through the plunger rod bore 47.

Threaded on the neck portion 43 of the casing part 36 is a sleeve nut 51. Sleeve nut 51 provides a convenient means for detachably connecting the casing of the dashpot device E to the support bracket plate 35. Sleeve nut 51 is provided with a reduced diameter outer end portion 52 that has a bore 53 therethrough adapted to loosely support and guide the outer end portion of the plunger rod 45. The bore 53 in the sleeve nut neck portion 52 is directly connected to the bore 44 in the casing part neck portion 43 and these aligned, connected bores are sufficiently larger than the outside diameter of the plunger rod 45 so that a clearance space or passage is provided therebetween for the ready transfer of air between the atmosphere and the interior of the casing chamber 42. Thus as the diaphragm 39 is flexed axially air may pass to and from the casing chamber 42 through the clearance spaces 53, 44 between the rod 45 and its supporting casing bores. Diaphragm 39 is continuously urged towards the left by the compression spring 55 that is mounted in the casing chamber 41 so as to extend between the casing and one of the diaphragm mounted washers 46.

Casing part 37 is formed with a bore or passageway 61 that connects the chamber 41 to a valve receiving bore 62. One end of the valve receiving bore 62 is closed off by a plug element 63 while the other end of the bore 62 receives the ball valve 64

and its operating mechanism that will subsequently be described in detail. Valve receiving bore 62 is of stepped construction to provide the valve seat 65. The reduced portion 66 of the valve receiving bore 62 slidably receives the push rod or actuator 67 for the valve 64. The lower end of the push rod 67 has the armature member 68 fixed thereto. Armature 68 is preferably of some ferrous material, or a similar material, so that it is responsive to magnetic attraction. Push rod 67 and its attached armature member 68 are normally urged upwardly by the compression spring 69 which action tends to hold the valve 64 off its seat 65. The spring 69 is seated in a recess 71 in the core element 72 of the electromagnetic solenoid unit 73.

The solenoid unit 73 has its coil element 74 surrounding and fixed to the core element 72 in more or less conventional manner. Electrical energy for the energization of the coil 74 is supplied thereto through the contact elements 76. Energization of the coil 74 will magnetize the core 72 such that armature element 68 will be attracted downwardly towards the core 72 and thereupon push rod 67 will be retracted sufficiently to permit the ball valve 64 to sink into engagement with its seat 65 and seal off the conduit connection between the valve receiving bore portions 62, 66.

The energization of the solenoid coil 74 is adapted to be automatically controlled by a vehicle speed responsive governor element 80. In the form herein disclosed the governor element 80 is of the flyball type and is drivingly connected by pinion gearing 81 (see Fig. 4) to a worm gear 82 carried by the vehicle drive train propeller shaft 23. It is thought to be obvious that other forms of vehicle speed responsive devices may be substituted for the governor 80 herein disclosed. Governor 80 is arranged to operate a switch contact 85. At low vehicle speeds and when the vehicle is at rest the governor 81 permits the spring 87 to cause engagement of the switch contact 85 with the switch contact 86. From Fig. 4 it is thought to be obvious that the solenoid coil 74 will be energized by the closing of contacts 85, 86 and the valve 64 will thereupon be closed. When the vehicle speed is increased to a predetermined speed the governor 80 will open contacts 85, 86 and at all vehicle speeds above this predetermined speed the contacts 85, 86 will remain open, the solenoid coil 74 will be deenergized and the valve 64 will be kept open by the spring 71.

The electrical circuit for control of the solenoid 73 is shown in Fig. 4 and comprises a source of electrical energy 89, such as a battery, that is grounded at 90 and connected by a conductor 91 through an ammeter 92 and an ignition switch 93 to one of the contacts 76 of the solenoid coil 74. Another contact 76 of coil 74 is connected by conductor 94 to the switch contact 86 that is engageable with the governor operated switch contact 85. Switch contact 85 is grounded at 95.

The casing of the dashpot device E includes in addition to the passage or bore 61 another bore or passageway 98. Bore 98 connects the casing chamber 42 to the reduced portion 66 of valve bore 62 that is located on the downstream side of the ball valve 64. With the arrangement disclosed it will be seen that when valve 64 is unseated or open then movement of the plunger rod 45 and the connected diaphragm 39 towards the right will force air out of chamber 41 through two different escape channels. The major portion of the air in chamber 41 may freely flow from chamber 41 through passage 61 into bore 62, through open valve 64 into bore 66 and thence through passage 98 into chamber 42 from whence it may escape to the atmosphere through the clearance spaces 44, 53 extending between the plunger rod 45 and the neck 43, 51 of the casing. At the same time that the air, or other medium contained in chamber 41, is passing between chambers 41 and 42 by the aforementioned escape route, a small percentage of the air in chamber 41 may escape from chamber 41 by a second route due to it being forced through plunger rod bore 47 and out through the cross-bore 48 to the aforesaid clearance passages 44, 53. It is apparent that only a small percentage of the air in

chamber 41 will pass by this latter escape route when valve 64 is open due to the fact that the restriction pin 49 in cross-bore 48 will cause most of the air in chamber 41 to pass through the open valve 64 and the large by-pass channel 98. It is thought to be rather obvious that when valve 64 is open that then dashpot E will offer very little resistance to movement of the rod 45 towards either the right or the left. However when valve 64 is seated and passage 61 is blocked off from passage 98 then on movement of the plunger rod towards the right the air escaping from chamber 41 must all pass through the second mentioned escape route, that is, through the bore 47 and the restricted opening in the cross-bore 48. Thus when valve 64 is closed there is only a single air escape passage for the air that is trapped in chamber 41 and as this escape passage comprises the restricted opening in cross-bore 48, it is thought to be obvious that during the times when the valve 64 is seated the dashpot device E provides a very definite retarding action on the movement of the plunger rod 45 towards the right. On the tendency for movement of the diaphragm 39 towards the left, when valve 64 is closed, it will be noted that there is no resisting or retarding effect offered by the closed valve 64 for the air or other medium in chamber 42 is forced out of chamber 42 back through by-pass 98 into bore portion 66 and up against the seated valve 64 such that valve 64 will be moved off its seat and the air in chamber 42 transferred back into the chamber 41. Thus it will be seen that the by-pass channel 98 has a material influence on the operation of the diaphragm whether the diaphragm is moved axially to the right or to the left.

The full lines in Fig. 1, as well as Fig. 2, indicate one of the preferred locations for the dashpot device E in a conventional motor vehicle chassis arrangement. Other possible locations for the dashpot device E in a motor vehicle chassis or body are indicated by the numerals 99 and 100 and are shown in broken lines in Fig. 1. It is thought to be obvious that the dashpot device E can be located at any point in a motor vehicle chassis or body provided it is arranged to have the dashpot plunger rod 45 engageable with some portion of the throttle valve control linkage or an extension thereof. In Figs. 1 and 2 the dashpot device E is shown mounted on the carburetor body by the bracket plate 35. The outer end of the dashpot plunger rod 45 is arranged so as to directly engage the throttle valve lever arm 24 that is fixed to the throttle valve support shaft 29. The outer end of rod 45 may be rounded as shown to reduce sliding friction between the rod 45 and the lever 24 during relative movement therebetween. Figs. 1 and 2 show the throttle valve and the associated dashpot mechanism in the closed throttle position of the throttle valve. This particular arrangement of the dashpot device E has the advantage of causing the dashpot plunger rod 45 to act directly on the throttle valve 23 and this eliminates the possibility of any slack or looseness in the throttle valve control linkage modifying or altering the intended action of the dashpot device. With properly designed throttle valve control linkages that are free of slack, it is obvious that any of the other locations 99 or 100 for the dashpot E would be equally as acceptable and this would have the further advantage that they remove the dashpot E from the vicinity of the carburetor which de-

vice is already surrounded by numerous engine control mechanisms.

With the arrangement shown in Figs. 1 and 2, it is apparent that on depression of the accelerator pedal 27 the throttle valve 23 and connected lever arm 24 will be rotated in a counterclockwise direction to accomplish opening of the throttle valve. During opening movement the lever arm 24 may move freely as the dashpot E has no effect whatever on throttle valve opening movement. The spring 55 of the dashpot E will cause the diaphragm 39 and connected push rod 45 to move towards the left and follow up the movement of the lever arm 24 during at least a portion of the throttle valve opening movement. As before mentioned the dashpot device E offers no retarding effect to leftward shift of the diaphragm 39 due to the fact that the air in chamber 42 may freely flow into the expanding chamber 41 regardless of the condition of valve 64. When the accelerator pedal 27 is released after throttle valve opening movement the lever arm 24 and valve 23 are urged clockwise to closed throttle position by the spring 28 and possibly by other resilient means not shown. The vehicle speed responsive governor 80 then automatically determines whether the dashpot E is to be effective to retard closing movement of the throttle valve. If the vehicle speed is above say 20 miles per hour then the contacts 85, 86 remain open and solenoid 73 is not energized so that valve 64 is open and the diaphragm 39 is easily shifted to the right due to the air in chamber 41 freely passing into chamber 42 and escaping to the atmosphere as previously described. Under such conditions engine braking is obtainable due to the rapid closing of the throttle valve. If on the other hand the vehicle speed should be below 20 miles per hour when the accelerator pedal 27 is released, then the governor 80 would have closed contacts 85, 86 and the solenoid 73 would be energized and valve 64 would be closed. Under these circumstances the movement of the plunger rod 45 towards the right by its engagement with the lever 24 on throttle valve closing movement causes the air in chamber 41 to escape by passing through the restricted opening in plunger rod cross bore 48. Thus a very definite retarding effect is applied to the closing movement of the throttle valve 23 when governor 80 has closed valve 64. The critical speed of 20 miles per hour for control of the solenoid 73 is purely a matter of choice and any other speed could be used that would accomplish the desired effect.

The invention hereinabove described is thought to provide an improved form of control for throttle valve closing movement that is simple, compact, free of any association with the fuel charge to the engine, not dependent on relative temperatures or pressure, and a device that can be easily and economically installed at any number of locations on the vehicle body or chassis.

In Figs. 5 and 6 I have shown a power transmission unit T in which the changes in speed ratio occur in response to release of the accelerator pedal. This type of power transmission is especially well suited for utilization of this invention due to the fact that this invention will insure fast speed ratio changes while preventing engine stall.

The transmission T comprises an input shaft 129 adapted to be driven by the engine crankshaft (not shown), an output shaft 121, a countershaft 122, and a countershaft gear cluster 119 rotatably mounted on the countershaft 122. Input pinion 123 carries clutch teeth 124 and a friction cone

10
15
20
25
30
35

125 that is constantly engaged by the blocker ring 116. The blocker 116 carries blocker teeth 126 adapted to be engaged by the blocker teeth 127 of clutch sleeve S when the latter sleeve S is biased forwardly under synchronous conditions in the rotation of pinion 123 and sleeve S. This sleeve S together with the clutch teeth 124 comprise relatively movable drive control elements for effecting step-up and step-down manipulation of the transmission.

Blocker 116 is lightly urged against the cone 125 by a spring 117 and has a lost-motion connection at 109 with the slotted end of a hub 108 of a high speed gear 123 such that the blocker 116 may move relative to sleeve S between two positions blocking the sleeve, such positions being known as the drive block and the coast block positions of the blocker ring 116 depending on whether pinion 123 appreciably leads or lags the speed of the sleeve S. The sleeve S is splined on hub 108 at 107, the arrangement being such that whenever sleeve S is rotating faster or slower than pinion 123 then the blocker teeth 126 will be aligned with the ends of the teeth of sleeve S and thus prevent shift of the sleeve S into contact with the pinion teeth 124. However, when the pinion 123 is rotating faster than sleeve S and gear 128 and the sleeve S is biased forwardly into blocked position, a reduction of engine speed will cause input shaft 128 and pinion 123 to slow down and as the pinion 123 and sleeve S pass through a synchronous relationship the blocker 116 is moved from its drive blocking position toward its coast blocking position and when substantially mid-way therebetween will unblock the sleeve S and allow the sleeve teeth 127 to pass between the blocker teeth 126 and clutch with pinion teeth 124.

Gear 123 is rotatably mounted on output shaft 121 but is keyed to the clutch sleeve S and is in constant engagement with countershaft cluster gear 129. Accordingly, countershaft cluster 119 may be power driven from gear 128 if sleeve S is engaged with pinion teeth 124. If sleeve S is urged to the right in Fig. 5 by the mechanism shown in Fig. 6 and disengaged from pinion teeth 124, the power drive of the countershaft cluster 119 occurs through pinion 123, gear 118 and overrunning clutch F.

A manually operated clutch G is adapted to either lock gear 128 to the driven shaft 121 or to lock gear 130 to the driven shaft 121. Gear 130 is in constant engagement with countershaft cluster gear 131. A reverse gear 132 is keyed to the output shaft 121 and is adapted to be selectively engaged with a shiftable idler gear (not shown) that is driven by the countershaft gear 131.

The manually operated clutch G has a splined connection with a hub 107 fixed to shaft 121. There is associated with clutch G any commercial type of blocker synchronizers 106 such that clutch G may be shifted either forwardly to high range or rearwardly to low range to synchronously clutch shaft 121 either with the high speed gear 128 at the teeth 105 or with the low speed gear 130 at the teeth 104. Manual shifts of clutch G are facilitated by release of a main clutch (not shown) that is operated by the usual clutch pedal.

There are four forward speeds which may be obtained from this transmission. The first two speeds occur when clutch G is shifted to the right in Fig. 5;

(a) A first speed when sleeve S is disengaged from teeth 124 and manual clutch G is locking

gear 130 to output shaft 121. The drive then occurs through pinion 123, gear 118, overrunning clutch F, countershaft cluster 119, gear 131, gear 130, and output shaft 121.

(b) A second speed when sleeve S is in engagement with teeth 124 and manual clutch G is locking gear 130 to output shaft 121. The drive then occurs through teeth 124, sleeve S, gear 128, gear 129, countershaft cluster 119, gear 131, gear 130, and output shaft 121.

If manual clutch G is shifted to the left in Fig. 5:

(c) A third speed when sleeve S is disengaged from teeth 124 and manual clutch G is locking gear 128 to output shaft 121. The drive then occurs through pinion 123, gear 118, overrunning clutch F, countershaft cluster 119, gear 129, gear 128, and output shaft 121.

(d) A fourth speed when sleeve S is in engagement with pinion teeth 124 and manual clutch G is locking gear 128 to output shaft 121. The drive then occurs through teeth 124, sleeve S, gear 128, and through clutch G to output shaft 121.

It should be noted that the engagement of sleeve S with pinion teeth 124 through the blocker device 116 is dependent upon synchronizing the speeds of rotation of gear 124 and sleeve S. Throttle control is directly related to the length of time required for this synchronization.

Fig. 6 illustrates automatic means for urging sleeve S into or out of engagement with pinion teeth 124 as discussed above and thereby accomplishing an automatic selection between the first and second or third and fourth speeds (depending upon the position of manual clutch G) as listed above. Fluid servomotor M controls shift of sleeve S. This motor comprises a cylinder 140 slidably receiving a piston 139 which slidably receives a rod 136 which is mounted to reciprocate in guideways 133 and 134. Fixed to this rod is the collar 137 of a yoke 138 connected with sleeve S to effect shift thereof. A relatively small force pre-loaded engaging spring 135 is disposed between piston 139 and yoke 138 to provide a lost motion thrust transmitting connection such that piston 139 may move forwardly or to the left for its power stroke being limited by abutment 103 in advance of the full clutching shift of sleeve S. The shift towards the left of the sleeve S is limited by engagement of the yoke collar 137 with the rear or exposed end of guideway 133. A relatively large force pre-loaded kickdown spring 141 is disposed between abutment 103 and piston 139 and serves to return the piston 139 and sleeve S to the downshifted Fig. 5 position. The spring 141 is thus adapted to effect disengaging bias of sleeve S relative to teeth 124.

Rod 136 has a shoulder 102 which in Fig. 5 engages the face of piston 139 but which, when the piston and rod 136 are moved to the end of their forward or upshifted strokes, is spaced rearwardly of the piston to provide a gap equal to the difference in the strokes of the piston 139 and rod 136. This gap is utilized to close an ignition control switch H for interrupting the engine ignition system. Piston 139 is provided with an annular groove 142 formed in its skirt to define a cam surface which operates switch H. Switch H interrupts the engine ignition to unload or relieve driving torque long enough to permit a disengagement of sleeve S from the pinion teeth 124.

A pressure fluid supply system is connected with the servomotor M by a passage 143 which

is connected to valve J. Pump 144 through tubing 145 draws oil from source 146. Pump 144 may be driven from some moving vehicle part, preferably a car speed responsive part such as a gear 253 on countershaft cluster 119. Pressure relief valve 147 permits the return of oil to the source 146 when the passage 143 is blocked off from conduit 145 by valve J. When valve J is raised above its Fig. 6 position by compressed spring 149 on de-energization of solenoid 148, passage 143 is connected to the oil pressure supply conduit 145 and piston 139 is moved towards the left to cause upshift of sleeve S. Solenoid 148, when energized, lowers valve J to its Fig. 6 position against the force of spring 149 which normally raises the valve J so that pressurized oil in line 145 is connected to line 143 and can cause motor M to shift sleeve S to the left.

Two parallel switches control the energizing of solenoid 148 which is electrically connected to the usual grounded storage battery 210 as illustrated in Fig. 6. Switch 250 is opened by a governor 251 driven at 253 (Fig. 5) when sufficient vehicle speed is obtained. Switch 252 is manually closed by depressing the accelerator pedal 27. The last portion of travel in depressing accelerator pedal 27 closes switch 252. Electrical circuit means for this purpose includes the grounded storage battery 210 for supply of electrical energy through ammeter 211, ignition switch 212, to a wire 213, thence through solenoid 148 to a terminal 214 from which either of two parallel grounds 215 or 216 will complete a circuit to energize solenoid 148 through wires 217 or 218a respectively.

The relation of the governor 251 to the system may be explained by an example. When manual clutch G of Fig. 5 is locking gear 128 to shaft 121 for normal driving in third or fourth forward speeds and the engine is idling with switch 250 closed and switch 252 open, solenoid 148 is energized and valve J closed. Therefore, sleeve S is not engaged with transmission pinion gear teeth 124 and operation will be in the third speed gear explained above driving directly from pinion 123 through countershaft cluster 119 and gear 128. The slip drive coupling that is connected between the engine and the transmission will permit the vehicle to remain stationary while the engine is idling. When the carburetor throttle valve is opened slightly the vehicle will be driven forward. When sufficient vehicle speed is obtained switch 250 is opened by governor 251 and solenoid 148 is deenergized. Spring 149 will open valve J and oil under pressure will be permitted to enter passage 143 and move piston 139 to the left thereby urging sleeve S to the left in Fig. 5 although it is restrained by blocker 116. When synchronous speeds of sleeve S and the pinion 23 are obtained by a release of the accelerator pedal 27 then the teeth of sleeve S pass through the blocker teeth 126 and engage the pinion teeth 124. The vehicle is then geared for drive in fourth speed or direct drive.

Governor 251 also initiates an automatic transmission downshift when vehicle speed is reduced sufficiently to cause the governor to close switch 250. This energizes solenoid 148, closes valve J, vents servomotor M and permits spring 141 to move piston 139 to the right momentarily interrupting engine ignition and through spring 141 and yoke 138 disengaging sleeve S from pinion gear teeth 124 and causing the drive to be downshifted to the third speed previously described.

The function of switch 252 is to provide means for the driver to selectively cause a downshift

from fourth speed to third speed, or if manual clutch G is in the low speed range position, from second speed to first speed. If when the vehicle is travelling in the direct drive fourth speed with switches 250 and 252 open, and for example a steep hill is encountered, the driver may push accelerator pedal 27 to its extreme down or throttle opening position and the aforementioned downshift to third speed will be achieved. Tooth 257 on arm 256 will close switch 252, ground the solenoid circuit at 216, thereby energizing solenoid 148 and by means of the venting of oil pressure from servomotor M and the action of spring 141 will move piston 139 towards the right interrupting engine ignition by switch H. Movement of piston 139 to the right will move yoke 138 and sleeve S to the right thereby creating the conditions necessary for the downshift to third speed. An automatic upshift back to fourth speed or direct drive will occur after release of accelerator pedal when the conditions are such as to dictate the upshift.

By the incorporation of the air dashpot device E of Figs. 1-4 in the transmission control system shown in Fig. 6, it is thought to be obvious that when the vehicle is travelling above the selected governor speed, say 15 to 20 miles per hour or thereabouts, that then the device E is inoperative to retard throttle valve closing movement and the release of the accelerator pedal 27 will permit the engine speed to drop down quickly to effect a quick synchronization of the speeds of pinion 123 and sleeve S. Accordingly, a fast change, either downshift or upshift, in speed ratio drive may be accomplished even with the dashpot E controlling the carburetor of a vehicle having a transmission similar to that shown in Fig. 5. However, when the vehicle speed is below the selected governor speed the dashpot device E will be operative to retard throttle valve closing movement and thus prevent engine stall. When the vehicle speed is below 15 M. P. H. then usually there will be no need or desire to release the accelerator 27 to accomplish the automatic speed ratio upshift. In initiating drive through the Fig. 5 transmission, the vehicle would normally be accelerated up beyond 15 or 20 miles per hour before the accelerator 27 would be released to accomplish the automatic upshift. Thus the dashpot device E is rendered inoperative to retard throttle closing movement before the accelerator controlled speed ratio change calls for a quick release of the throttle valve to accomplish the upshift.

I claim:

1. A dashpot device for modifying the normal movement of a control valve or the like comprising a casing having a pair of chambers separated by a flexible, anchored, diaphragm, a plunger element carried by said diaphragm having a portion adapted to be engaged with said control valve, resilient means normally urging said diaphragm in a direction tending to contract one of said chambers, an air inlet to one of said chambers, a first passageway connecting said chambers, and a second passageway connecting said chambers, said first passageway including means arranged such that the passage of the air medium between said chambers through said first passageway is materially retarded as compared to the passage of the air medium between 70 said chambers through said second passageway.

2. A dashpot device for modifying the normal movement of a control valve or the like comprising a casing having a pair of chambers separated by a flexible, anchored, diaphragm, a plunger 75

element carried by said diaphragm having a portion adapted to be engaged with said control valve, resilient means normally urging said diaphragm in a direction tending to contract one of said chambers, an air inlet to one of said chambers, a first passageway connecting said chambers, a second passageway connecting said chambers, said first passageway including means arranged such that the passage of the air medium between said chambers through said first passageway is materially retarded as compared to the passage of the air medium between said chambers through said second passageway, and valve means associated with said second passageway to control the interchange of the air medium between said chambers through said second passageway.

3. A dashpot device for modifying the normal movement of a control valve or the like comprising a casing having a pair of chambers separated by a flexible, anchored, diaphragm, a plunger element carried by said diaphragm having a portion adapted to be engaged with said control valve, resilient means normally urging said diaphragm in a direction tending to contract one of said chambers, an air inlet to one of said chambers, a first passageway connecting said chambers, a second passageway connecting said chambers, said first passageway including means arranged such that the passage of the air medium between said chambers through said first passageway is materially retarded as compared to the passage of the air medium between said chambers through said second passageway, and valve means associated with said second passageway to control the interchange of the air medium between said chambers through said second passageway, and means to automatically operate said valve means.

4. A dashpot device for modifying the normal movement of a control valve or the like comprising a casing having a pair of chambers separated by a flexible, anchored, diaphragm, a plunger element carried by said diaphragm having a portion adapted to be engaged with said control valve, resilient means normally urging said diaphragm in a direction tending to contract one of said chambers, a gas inlet to one of said chambers, a first passageway connecting said chambers, and a second passageway connecting said chambers, said first passageway including a restrictive opening arranged such that the passage of the gas medium between said chambers through said first passageway is materially retarded as compared to the passage of the gas medium between said chambers through said second passageway.

5. A dashpot device for modifying the normal movement of a control valve or the like comprising a casing having a pair of chambers separated by a flexible, anchored, diaphragm, a plunger element carried by said diaphragm having a portion adapted to be engaged with said control valve, resilient means normally urging said diaphragm in a direction tending to contract one of said chambers, a gas inlet to one of said chambers, a first passageway connecting said chambers, a second passageway connecting said chambers, said first passageway including a portion with a plug element arranged therein with clearance space extending thereabouts arranged such that the passage of the gas medium between said chambers through said first passageway is materially retarded as compared to the passage of the gas medium between said chambers through 75 said second passageway, and valve means asso-

ciated with said second passageway to control the interchange of the gas medium between said chambers through said second passageway.

6. An air dashpot for controlling closing movement of a carburetor throttle valve comprising a casing having a pair of adjacent chambers separated by a flexible, anchored, diaphragm element, a plunger rod extending through the casing and one of the chambers having portions connected to said diaphragm for movement thereby and another portion engageable with the throttle valve, an air inlet to said one chamber, a first air passageway extending through said diaphragm having restriction means associated therewith to meter the interchange of air between said chambers through said first passageway, a second air passageway extending between said chambers, a valve mounted in said second passageway adapted to be closed to seal off communication between said chambers through said second passageway, resilient means normally opening said valve to provide a pair of passageways to transfer air between said chambers on movement of said plunger rod, and electrically operated means to effect closing of said valve to cause the interchange of air between said chambers to be through said first passageway whereby the restriction means therein produces a dashpot action that retards shift of the plunger rod in one direction.

7. An air dashpot for controlling closing movement of a carburetor throttle valve comprising a casing having a pair of adjacent chambers separated by a flexible, anchored, diaphragm element, a plunger rod extending through the casing and one of the chambers having portions connected to said diaphragm for movement thereby and another portion engageable with the throttle valve, an air inlet to said one chamber, a first air passageway extending through said diaphragm having restriction means associated therewith to meter the interchange of air between said chambers through said first passageway, a second air passageway extending between said chambers, a valve mounted in said second passageway adapted to be closed to seal off communication between said chambers through said second passageway, resilient means normally opening said valve to provide a pair of passageways to transfer air between said chambers on movement of said plunger rod, a solenoid energizable to effect closing of said valve and electrical circuit means for said solenoid to automatically control energization of said solenoid.

8. An air dashpot for controlling closing movement of a motor vehicle engine carburetor throttle valve comprising a casing having a pair of adjacent chambers separated by a flexible, anchored, diaphragm element, a plunger rod extending through the casing and one of the chambers having portions connected to said diaphragm for movement thereby and another portion engageable with the throttle valve, an air inlet to said one chamber, a first air passageway extending through said diaphragm having restriction means associated therewith to meter the interchange of air between said chambers through said first passageway, a second air passageway extending between said chambers, a valve mounted in said second passageway adapted to be closed to seal off communication between said chambers through said second passageway, resilient means normally opening said valve to provide a pair of passageways to transfer air between said chambers on movement of said

plunger rod, a solenoid energizable to effect closing of the valve, and an electrical circuit means connected to said solenoid including a vehicle speed responsive switch to automatically control energization of the solenoid.

9. An air dashpot device adapted to have a portion thereof engaged with the throttle valve control of an internal combustion engine carburetor to provide for selective retardation of the closing movement of the throttle valve comprising a casing having a pair of adjacent air chambers separated by a flexible, anchored, diaphragm, resilient means normally urging said diaphragm in a direction tending to contract one of said chambers, a plunger rod piercing said casing, the said one chamber and said diaphragm and fixedly connected to said diaphragm for movement therewith, said plunger rod having a portion engageable with the throttle valve, a bore in said plunger rod providing a first passageway interconnecting said chambers, restriction means associated with said bore to meter the air passing through said bore, an air inlet to said one chamber, a second passageway connecting said chambers including a stepped bore providing a valve seat, a ball valve engageable with said seat, a push rod slidably mounted in said stepped bore and engageable with said ball valve to effect unseating thereof, resilient means normally urging

said push rod into engagement with said ball valve, solenoid means energizable to disengage said push rod from said ball valve to seat said valve, and electrical circuit means for said solenoid to automatically control energization thereof.

10. In a motor vehicle, an air dashpot device adapted to have a portion thereof engaged with the throttle valve control of the motor vehicle internal combustion engine carburetor to provide for selective retardation of the closing movement of the throttle valve comprising a casing having a pair of adjacent air chambers separated by a flexible, anchored, diaphragm, resilient means normally urging said diaphragm in a direction tending to contract one of said chambers, a plunger rod piercing said casing, the said one chamber and said diaphragm and fixedly connected to said diaphragm for movement therewith, said plunger rod having a portion engageable with the throttle valve, a bore in said plunger rod providing a first passageway interconnecting said chambers, restriction means associated with said bore to meter the air passing through said bore, an air inlet to said one chamber, a second passageway connecting said chambers including a stepped bore providing a valve seat, a ball valve engageable with said seat, a push rod slidably mounted in said stepped bore and engageable with said ball valve to effect unseating thereof, resilient means normally urging said push rod into engagement with said ball valve, solenoid means energizable to disengage said push rod from said ball valve to seat said valve, and electrical circuit means for said solenoid to automatically control energization thereof comprising a vehicle speed responsive switch to energize said solenoid below a predetermined vehicle speed so as to thereupon close off said second passageway and activate the dashpot to retard throttle valve closing movement.

11. In a motor vehicle, an air dashpot device adapted to have a portion thereof engaged with the throttle valve control of the motor vehicle internal combustion engine carburetor to provide for selective retardation of the closing movement

15

of the throttle valve comprising a casing having a pair of adjacent air chambers separated by a flexible, anchored, diaphragm, resilient means normally urging said diaphragm in a direction tending to contract one of said chambers, a plunger rod piercing said casing, the said one chamber and said diaphragm and fixedly connected to said diaphragm for movement therewith, said plunger rod having a portion engageable with the throttle valve, a bore in said plunger rod providing a first passageway interconnecting said chambers, restriction means associated with said bore to meter the air passing through said bore, an air inlet to said one chamber, a second passageway connecting said chambers including 15 a first by-pass portion connected between said one chamber and a push rod receiving bore, a second by-pass portion connected between the other chamber and the push rod receiving bore,

5
10

16

a valve in said push rod receiving bore intermediate the connections of the by-pass portions to the push rod receiving bore, a push rod slidably mounted in said push rod receiving bore, resilient means normally urging said push rod into engagement with said valve to open said valve, solenoid means energizable to disengage said push rod from said valve to close said valve, and an electrical circuit for said solenoid including vehicle speed responsive control means to automatically control energization of said solenoid.
